United States Patent Office

Des. 194,598
Patented Feb. 19, 1963

194,598

TILE OR SIMILAR ARTICLE

Philip M. Brody, Scarsdale, and Frederic H. Rahr, New York, N.Y., assignors to Wood Conversion Company, St. Paul, Minn., a corporation of Delaware

Filed Apr. 27, 1961, Ser. No. 64,926

Term of patent 14 years

(Cl. D18—2)

FIG. 1

FIG. 2 3 3

FIG. 3

FIG. 1 is a top plan view of a tile or similar article showing our new design.

FIG. 2 is a top plan view of a tile showing a modified form of the design of our invention.

FIG. 3 is an enlarged fragmentary cross-sectional view of FIG. 2 taken on line 3-3 thereof.

We claim:

The ornamental design for a tile or similar article, substantially as shown and described.
